MINER'S LANTERN

Sylvia Zedlar, G.P.O. Box 2925,
New York, N.Y. 10001

Filed Apr. 21, 1969, Ser. No. 16,830

Term of patent 7 years

Int. Cl. D26—04

U.S. Cl. D48—24

FIG. 3

FIG. 1

FIG. 2

FIG. 1 is a perspective view taken from above of the lantern embodying my new design;

FIG. 2 is a side elevational view thereof on an enlarged scale;

FIG. 3 is a top plan view thereof on an enlarged scale.
I claim:

The ornamental design for a miner's lantern, as shown.
